UNITED STATES PATENT OFFICE.

JOHN S. O'CONNOR, OF WHITE MILLS, PENNSYLVANIA.

DESIGN FOR THE ORNAMENTATION OF GLASSWARE.

SPECIFICATION forming part of Design No. 21,424, dated March 22, 1892.

Application filed February 18, 1892. Serial No. 422,039. Term of patent 7 years.

To all whom it may concern:

Be it known that I, JOHN S. O'CONNOR, a citizen of the United States, residing at White Mills, in the county of Wayne and State of Pennsylvania, have invented and produced a new and original Design for the Ornamentation of Glassware, of which the following is a specification, reference being had to the accompanying drawings, forming part thereof.

10 Figure 1 is a view of a glass dish having my design applied thereto, the dish being shown in plan. Fig. 2 is a sectional view thereof.

As will be seen by reference to the drawings, the center of the bottom of the dish is occupied by star-shaped figure A, formed of a plurality of stars, one within the other, and surrounded by a decagon B. Between this figure and the outer edge of the receptacle are formed loops, as shown at C, and from 15 the upper and outer points of which diverge a series of lines, forming fan-shaped figures D,

extending to the said edge of the receptacle, which is scalloped, as plainly appears in Fig. 2 at E. The surface inclosed within the loops C is filled with the intersecting lines F, while 25 the spaces between the adjacent loops are filled with star-shaped figures G, similar to the larger central figure A, and also with the intersecting lines, as shown at H, separated from said small star-shaped figures G by several parallel lines I, joining the adjacent loops 30 C, above referred to.

Having thus described my new and original design for the ornamentation of glass receptacles, what I claim is—

35 The design for the ornamentation of glass-ware, as herein shown and described.

JOHN S. O'CONNOR.
